United States Patent Office.

CALVIN W. SHERWOOD, OF CHICAGO, ILLINOIS.

Design No. 2,557, dated January 15, 1867.

DESIGN FOR A STANDARD FOR SCHOOL FURNITURE.

The Schedule referred to in these Letters Patent and making part of the same.

TO ALL WHOM IT MAY CONCERN:

Be it known that I, CALVIN W. SHERWOOD, of the city of Chicago, county of Cook, and State of Illinois, have originated and produced a new Design for Standards for School Furniture, of which the following is a full, clear, and exact description, reference being had to the accompanying photograph of the same, making part of this specification.

The photograph shows a school desk and seat, the same being made separate.

The wooden portions of the desk are attached to iron standards A, of peculiar and useful form, and ornamented, as shown, while the wooden portions of the seat are attached to other iron standards, B, adapted to the purpose, of form and style as shown; the two together making a complete desk and seat for the school-room.

What I claim as my invention, and desire to secure by Letters Patent, is the design for standards A and B for school furniture, as herein described and shown in the accompanying photograph.

C. W. SHERWOOD.
